METHOD AND APPARATUS FOR STITCHING
UP WOOL BALES AND LIKE FABRIC CON-
TAINERSVictor Zeckendorf, Sea Point, Cape Town, Cape of
Good Hope, Union of South AfricaApplication June 14, 1940, Serial No. 340,612
In Great Britain June 15, 1939

15 Claims. (Cl. 112—11)

This invention relates to an improved method of stitching up wool bales and the like and to the apparatus for carrying the method into practice. The invention is applicable for carrying out the closing stitching operation in which the closure flap, usually attached to the top edge of one side of a bale, is stitched to the top edges of the other three sides. Previously this operation, which has been done by hand, has been a tedious process. The present invention aims at 10 enabling it to be accomplished in a fraction of the time taken by this hand stitching method.

According to the invention broadly, it is proposed to provide means positioned adjacent the top edges of the bale which, besides holding said edges during the filling operation, cause the material adjacent said top edges to be formed into a plurality of folds or open pleats, so that when the edges of the cover flap are, by means of hooked retaining members, made to conform to said folds, the two edges are adapted to be stitched together for closing purposes by passing a thread one or more times through said folds by means of an elongated needle.

More particularly the apparatus as used for a wool bale consists of a rectangular head frame surrounding the bale top so that the top edges thereof are readily adapted to be engaged with the holding means above referred to. The folds or pleats are formed by a plurality of spaced pleat-forming members which are so positioned that they tend to press the bale sides inwardly in a series of shallow folds or corrugations adjacent their top edges. Hooked retaining members are arranged to operate between each of said members so that on engagement with the edges of the cover flap, said edges are drawn by the hooked members into the folds referred to, to permit of the passing of the elongated needle therethrough in succession from the outside. It will be understood from the foregoing description that the passing of a thread or threads through the folds, actually stitches the top edges of the bale to the edges of the cover flap in what is in effect a single operation. Normally the cover flap of a wool bale is permanently attached to one top edge so that three edges only have to be stitched. From this it will be understood that a unit of the apparatus is provided for each of the three sides, which units are however interconnected so that they may be made to operate simultaneously for bale suspending and bale releasing purposes. As the several units are of similar construction, a description will now be 55

given of a single unit constructed according to the invention.

Each unit consists of a holding bar mounted for partial rotation about its own axis and positioned parallel with and adjacent the top edge of the bale. A row of spaced bale supporting prongs project from this bar by means of which each top edge of the bale is adapted to be hung for the purpose of holding the bale open and suspended during the filling operation. Partial rotation of said bar by means of a control lever, releases the bale from the said prongs on completion of the stitching operation. This control lever in the normal holding position of the prongs, projects downwardly and is held in such position by a retaining stop fixed to a supporting framework which extends from floor level and supports the head frame at the correct height.

Projecting from a separate supporting bar, mounted behind the holding bar for pivoting movement, about an axis below the axis of the holding bar, is a row of pleat-forming members which consist of downwardly curved metal fingers, so arranged that when an edge of the bale 20 is engaged over the supporting prongs, they press the material adjacent said edge inwardly in a plurality of folds or pleats. The action is such that the unsupported portions of the edge between each retaining prong sag into the spaces 25 between each pleat-forming member. The free ends of the pleat-forming members may be supported in holes, slots or the like, provided in the aforementioned head frame member.

The downwardly folded edge of the cover flap 30 is held in conforming contact with the folds or pleats referred to, by a gang of hooked retaining members arranged in spaced relationship on a rod or bar arranged for sliding movement into 35 and out of the operative position. The said rod or bar is located beneath the row of pleat-forming members and the hooked members are so spaced thereon that they register with the spaces between said pleat-forming members.

To enable the invention to be more clearly understood and carried into practice, reference is now made to the accompanying sheets of drawings in which like reference numerals denote like parts throughout the several views.

In the drawings—

Fig. 1 is a side elevation of an apparatus constructed according to the invention.

Fig. 2 is a plan view taken on Fig. 1.

Fig. 3 is a fragmentary plan view, drawn to an enlarged scale, of the top left hand corner of the apparatus shown in Fig. 2.

Fig. 4 is a vertical sectional view taken on line IV—IV of Fig. 3.

Fig. 5 is a vertical sectional view taken on line V—V of Fig. 3.

Fig. 6 is another vertical sectional view taken on line VI—VI of Fig. 3, and

Fig. 7 is a shortened elevation of the elongated needle and its holder, and

Fig. 8 is a fragmentary end sectional view of a modified arrangement.

Referring to the drawings reference 1 denotes a rectangular metal framework or stand supporting the head frame carrying the several units, at an appropriate height with respect to a wool bale shown in chain dotted outline at 2 in the filling position. The head frame consists essentially of a base plate 3 to which the several parts of each unit are fixed. The apparatus as illustrated is arranged for wool bales in which the cover flap is permanently secured to one top edge. This requires complete units only on the three remaining sides for stitching purposes.

Since the three units are identical, a description will be given of one of them. Each unit consists essentially of a holding bar 4 rotatably mounted at each end in brackets 5 bolted to the base plate 3, pleat-forming metal fingers 6 projecting from a separate supporting bar 7 mounted for pivoting movement about an axis constituted by the pivot pins 8, and a gang of retaining hooks 9 projecting from a carrying bar 10 which is mounted for sliding movement by means of guide pins 11 co-acting with brackets 12. The holding bar 4 is provided with a row of bale-supporting prongs 13 and is arranged to be partially rotated by lever arm 14, link 15 and lever arm 16 keyed to a control shaft 18, journalled in bearing brackets 17 bolted to the supporting framework 1. The control shafts 18 are interconnected by the bevel pinions 19, and one of them at what is the front of the apparatus, is operated by a cranked control lever 20. By this arrangement all the holding bars 4 are rotated simultaneously for bale suspending or bale releasing purposes.

Movement of the pleat-forming fingers 6 into and out of their operative positions is effected by means of toothed portions 21 of the holding bar 4 which mesh with toothed sector gears 22 pivoted on the pins 8 and carrying between them the bar 7 from which said fingers project after the manner of the prongs of a rake. As clearly indicated in Figs. 4, 5 and 6, the bar 7 is positioned at the back of the holding bar 4, in which latter element clearance slots 23 are provided to enable the fingers 6 to move to their maximum forward operative positions as clearly shown in Fig. 4.

The retaining hooks 9 are moved into and out of their operative positions by means of links 24, lever arms 25 and hand levers 26. As shown, the lever arms 25 and the hand levers 26 are attached to sleeves 27 rotatably mounted on the control shafts 18.

The actual stitching operation is done by an elongated needle 28 held in a handled needle holder 29. The needle 28 is arranged to be guided in a straight line so as to pass through the folds in succession by means of a grooved guide 30 fixed to the base plate 3, in the groove of which the bottom member 31 of the needle holder 29 is adapted to be a sliding fit. In order to secure relatively deep folds in the top edges of the bale, the inner edges of the base plate 3 are preferably scalloped as shown in Fig. 3, in such a manner that the projections or tongues coincide with the curved metal fingers 6, while the

valleys or depressions coincide with the retaining hooks 9. To enable the hooks 9 to engage with the bale as near its top edges as possible, the carrying bar 10 is arranged for sliding movement close to the underside of the holding bar 4, and clearance slots 32 are provided therein through which the hooks 9 pass (see Fig. 6).

A description will now be given of the actual operation of the apparatus in connection with a wool bale in which the cover flap is permanently attached to one top edge. First of all the hand lever 20 is pulled outwardly which action causes all the holding bars 4 to rotate clockwise until the bale supporting prongs 13 project inwardly in more or less horizontal positions as indicated by the dotted outline in Fig. 5. The hand levers 26 are likewise pulled outwardly, which action causes the retaining hooks 9 to move inwardly from the position shown in Fig. 6 to the position shown in Fig. 4. The top edges 41 of the empty bale 2 are then in turn pulled up and impaled on the prongs 13 after the points of the hooks 9 have in turn been forced through the fabric of the bale side adjacent the top edges, as indicated in Fig. 6. The rear side of the bale will of course be hung on the rear holding bar which is the one on the right hand side of Figs. 1 and 2. It will be noted that the other parts of the unit have been omitted from this side since the apparatus, as shown, is intended for use with bales having an attached cover flap.

The hand lever 20 is now moved inwardly whereby the holding bars 4 are rotated to bring their prongs 13 to the position shown in Fig. 4. The hand lever 20 is then locked in this position by means of the notched bracket 39. The bale is now ready for filling. When the filling operation is completed the cover flap 40 (Fig. 6) is pulled over the open top and the downwardly folded edges 42 thereof are in turn hooked on to the inwardly protruding pointed ends of the hooks 9. Thereafter the hand levers 26 are in turn moved inwardly which action pulls the overlapping edge portions of the cover flap snugly into the folds as indicated in Fig. 6. In this position the bale is ready for the stitching operation. The needle holder 29 with the needle 28 threaded, is now placed with the end of the member 31 in engagement in the groove of a guide 30, and by a sliding movement the needle is pushed through the folds in succession one or more times. The position of the needle for this purpose is shown in Fig. 6. It will be understood that this stitching operation, by passing a thread through the folds between the curved fingers 6 and the hooks 9, actually stitches the cover flap to the edge of the bale by reason of the fact that the thread is passed alternately in and out through the double thickness of fabric.

After each of the three sides has been stitched in this manner, the hooks 9 are again moved inwardly by an outward pull on all the hand levers 26. The holding bars 4 are then rotated in a clockwise direction until the bale edges slip off the supporting prongs 13. Thus released the bale drops and is thereby disengaged from the hooks 9. As described earlier in the specification, partial clockwise rotation of the holding bars 4, causes the curved metal fingers 6 to move upwardly and outwardly, whereby they automatically disengage themselves from the stitches as the bale is lowered to the point where it is released from the holding prongs 13.

It will be understood that, since the bottom member 31 of the needle holder 29 is in no way

fixed as regards its guide groove 30, the needle 28 may be moved in a restricted arcuate path until the best position for the stitches is found.

In the modified arrangement shown in Fig. 8, the retaining hooks 9a are arranged to operate on the inside of the holding bar 4a which is provided with clearance slots 32a, to permit of the necessary horizontal movement of said hooks. This construction allows the hooks 9a to be positioned close to the retaining prongs 13 in their raised or operative position, thereby making it possible for the edges of the bale to be slipped under the pointed ends of said hooks 9a and then attached to the prongs 13. It will be understood that this arrangement obviates the necessity of forcing the points of the retaining hooks through the bale fabric as previously described. It also permits of the stitching of the cover flap closer to the top edges of the bale sides. In this construction the pleat-forming fingers 6a may be arranged to pass through clearance holes 23a in the holding bar 4a.

The frame 1 is preferably mounted on rollers or castors 34 to permit of its being easily moved from one place to another.

What I claim is:

1. A method of closing a wool bale and similar fabric container, comprising holding the top edges of said bale during the filling operation, then forming the material of said bale adjacent said top edges into a plurality of folds, then placing a cover flap over said filled bale, then forming the edges of said cover flap into folds conforming with the folds formed in the top edges of said bale and then passing securing means through the folds in said bale and said cover flap which are in conformity.

2. A method of closing a wool bale and similar fabric container, comprising holding the top edges of said bale during the filling operation, then forming the material of said bale adjacent said top edges into a plurality of folds, then placing a cover flap over said filled bale, then forming the edges of said cover flap into folds conforming with the folds formed in the top edges of said bale, and then passing a threaded needle transversely through said folds in said bale and said cover flap which are in conformity.

3. A method of closing a wool bale or similar fabric container having a cover flap attached to one of the upper edges thereof comprising suspending said bale adjacent the top edges thereof during the filling operation, forming folds in the material of said bale adjacent said top edges, then inserting the edges of said cover flap between the material in said filled bale and the interior surfaces of said top edges of said bale, then pulling said edges of said cover flap into conformity with the folds in the material of said bale adjacent the top edges thereof and then securing said folds of said bale and said cover flap.

4. A method of closing a wool bale or similar fabric container having a cover flap attached to one of the upper edges thereof comprising suspending said bale adjacent the top edges thereof during the filling operation, forming folds in the material of said bale adjacent said top edges, then inserting the edges of said cover flap between the material in said filled bale and the interior surfaces of said top edges of said bale, then pulling said edges of said cover flap into conformity with the folds in the material of said bale adjacent the top edges thereof, and then passing a threaded needle transversely through said folds

in said bale and said cover flap which are in conformity.

5. An apparatus for stitching a wool bale or similar four-sided fabric container comprising a rectangularly shaped head frame, means on said frame for releasably holding the top edges of the four sides of said bale, a plurality of spaced pleat-forming members mounted on said frame for forming a series of folds in the material of said bale adjacent its top edges, said folds being formed merely by the weight of the bale depending from the aforesaid releasable holding means, and a series of retaining members located between said pleat-forming members also mounted upon said frame for drawing the edges of a cover flap into a snug fit with said folds so that said cover flap may be easily stitched to the top edges of said bale.

6. An apparatus for stitching a wool bale or similar four-sided fabric container comprising a rectangularly shaped head frame, means on said frame for releasably holding the top edges of the four sides of said bale, a plurality of spaced pleat-forming members mounted on said frame for forming a series of folds in the material of said bale adjacent its top edges, said folds being formed merely by the weight of the bale depending from the aforesaid releasable holding means, and a series of retaining members located between said pleat-forming members also mounted upon said frame for drawing the edges of a cover flap into a snug fit with said folds, and a guide positioned upon said frame adjacent said folds for guiding a threaded needle to stitch said folds.

7. An apparatus for stitching a wool bale or similar four-sided fabric container, comprising a frame, releasable holding means for the top edges of the four sides of said bale mounted upon said frame, means for operating said holding means simultaneously, a series of spaced pleat-forming members also positioned on said frame to form a series of shallow folds in the top edges of said bale, said folds being formed merely by the weight of the bale depending from the aforesaid releasable holding means, and a series of retaining members also positioned upon said frame intermediate said pleat forming members to draw the edges of a cover flap snugly into contact with said folds so that said folds may be secured together.

8. An apparatus for stitching a wool bale or similar four-sided fabric container comprising a frame, releasable holding means for the top edges of the four sides of said bale mounted upon said frame, means for operating said holding means simultaneously, a series of spaced pleat-forming members also positioned on said frame to form a series of shallow folds in the top edges of said bale, said folds being formed merely by the weight of the bale depending from the aforesaid releasable holding means, and a series of retaining members also positioned upon said frame intermediate said pleat forming members to draw the edges of a cover flap snugly into contact with said folds, and a guide member located upon said frame adjacent said folds along which a threaded needle may be guided so as to thread a thread through said folds.

9. An apparatus for stitching a wool bale or similar four-sided fabric container, comprising a frame, releasable holding means for the top edges of the four sides of said bale mounted upon said frame, means for operating said holding means simultaneously, a series of spaced pleat forming members also positioned on said frame to form a series of shallow folds in the top edges of said

bale, said folds being formed merely by the weight of the bale depending from the aforesaid releasable holding means, and a series of retaining members also positioned upon said frame intermediate said pleat forming members to draw the edges of a cover flap snugly into contact with said folds, and sewing means reciprocal upon said frame for sewing said folds together.

10. An apparatus for closing a wool bale or similar fabric container comprising a holding bar mounted for partial rotation about its own axis and positioned parallel with and adjacent a top edge of the bale, said bar being provided with a row of spaced bale supporting prongs, a row of pleat-forming members in the shape of downwardly curved fingers operating in conjunction with the holding bar into and out of their operative positions, and a gang of hooked retaining members positioned below said holding bar and independently slidably into and out of their operative positions by means of separate control means.

11. An apparatus for closing a wool bale or similar fabric container comprising a holding bar mounted for partial rotation about its own axis and positioned parallel with and adjacent a top edge of the bale, said bar being provided with a row of spaced bale supporting prongs, a row of pleat-forming members in the shape of downwardly curved fingers operating in conjunction with the holding bar into and out of their operative positions, and a gang of hooked retaining members positioned below said holding bar and independently slidably into and out of their operative positions by means of separate control means, a supporting bar pivotally mounted behind said holding bar for pivoting movement on an axis below the axis of said holding bar, said pleat-forming fingers projecting from said supporting bar, a gear on said holding bar, a toothed 40

sector on said supporting bar meshing with said gear so that upon rotation of said holding bar for bale suspending purposes, said fingers will be moved inwardly and downwardly to their operative positions, and upon rotation of said holding bar for bale releasing purposes said fingers will be withdrawn inwardly and outwardly away from their operative positions and thereby released from the bale.

12. An apparatus for stitching a wool bale or similar fabric container comprising a frame, releasable holding means for the top edges of said bale mounted upon said frame, means for operating said holding means simultaneously, a series of spaced pleat-forming members also positioned on said frame to form a series of shallow folds in the top edges of said bale and a series of retaining members also positioned upon said frame intermediate said pleat-forming members to draw the edges of a cover flap snugly into contact with said folds, a holder frame, an elongated needle for stitching said folds together mounted in said holder frame, and a guiding member located on said frame parallel with and beneath said releasable holding means for said holder frame.

13. A construction as set forth in claim 10, wherein said holding bar is provided with clearance slots for said fingers and said hooked retaining members.

14. A construction as set forth in claim 10, in which a plurality of holding bars are provided and means for simultaneously operating said holding bars.

15. A construction as set forth in claim 5, in which said frame is provided with scallops provided in the edge of a plate forming the top of said frame conforming to the folds produced by said pleat-forming members.

VICTOR ZECKENDORF.
